Daniel J. Dunbar,
BY Joshua P. Koffe,
HIS ATTORNEY

UNITED STATES PATENT OFFICE.

DANIEL J. DUNBAR, OF PHILADELPHIA, PENNSYLVANIA.

SASH.

1,192,999.

Specification of Letters Patent.

Patented Aug. 1, 1916.

Application filed December 21, 1915. Serial No. 67,974.

To all whom it may concern:

Be it known that I, DANIEL J. DUNBAR, a citizen of the United States, residing at Philadelphia, in the county of Philadelphia 5 and State of Pennsylvania, have invented certain new and useful Improvements in Sashes, of which the following is a specification.

My invention relates to improvements in 10 sashes, and more particularly to improved means for securing the glass pane in the frame, so that the joint will be strong, durable, and practically air tight, and prevent all movement of the pane in the frame.

15 A further object is to provide a sash which can be manufactured at a reasonably low price, and which permits the ready removal of a broken pane, and the substitution of a new one whenever required.

20 With these and other objects in view, the invention consists in certain novel features of construction and combinations and arrangements of parts as will be more fully hereinafter described and pointed out in the 25 claims.

In the accompanying drawings: Figures 1 and 2 are views in elevation of opposite sides of a window sash embodying my improvements, and Fig. 3 is an enlarged view 30 in section on the line 3—3 of Fig. 1.

1, 1, represent the vertical stiles connected by horizontal rails 2, 2, forming a frame supporting a sash pane 3. Inside of the sash frame formed by stiles 1, and rails 2, 35 I secure a glazing frame 4 which comprises four metal strips 5 secured together at their ends by solder, or otherwise connected to form a frame which neatly fits within the sash and is secured by nails 6.

40 Each strip 5 is bent longitudinally forming an inner leaf 7 and an outer leaf 8. The inner leaf 7 is relatively flat and is secured against the stiles of rails of the sash by nails 6 or other suitable securing devices. The 45 outer leaf 8 is of general curved form, and at its edge bears against the sash pane 3.

As shown clearly in Fig. 3, the leaf 7 projects inwardly a distance beyond the edge of leaf 8, or in other words, a distance 50 at least equal to the thickness of the pane 3. It will also be noted that the pane 3 at its edge is spaced slightly from the leaf 7, so that a filling of plastic material 9 in the strip bears against the edge of the pane as 55 well as against the face of the pane, and constitutes a seal to render the sash air tight.

I use this term "plastic material" to cover cement, putty, or any similar material which can be used in a plastic state and which afterward hardens and I have found 60 by experiment that cement answers the purpose very effectually.

The pane 3 is securely held against the glazing frame 4 by glazing strips 10 which are secured to the stiles and rails of the sash by nails 11. These glazing strips 10 are 65 preferably of wood and they can be easily removed from time to time to permit a broken pane to be replaced.

In constructing the sash, the glazing 70 frame 4 is first secured by means of its nails 6, and the plastic material 9 is inserted in the glazing frame. The pane 3 is then pressed into the plastic material 9 until its movement is stopped by the free edge of 75 leaf 8, when it will be noted that the edge of the pane will be embedded in the plastic material, and after the strips 10 are secured, the sash will be air tight.

It will be noted that the leaf 7 is sufficiently long to accommodate the plastic material 9 at the edge of the pane 3, and that I utilize the difference in length of leaves 7 and 8 to properly locate the pane 80 and house the plastic material.

85 Various slight changes might be made in the general form and arrangement of parts described without departing from my invention, and hence I do not limit myself to the precise details set forth, but consider 90 myself at liberty to make such changes and alterations as fairly fall within the spirit and scope of the appended claims.

Having thus described my invention, what I claim as new and desire to secure 95 by Letters Patent is:

1. The combination with a main sash frame, of a glazing frame secured in the sash frame, said glazing frame comprising metal strips bent forming two leaves, one 100 leaf of each strip relatively flat and coincident with a surface of the main sash frame and secured to said surface, the other leaf curved and shorter than the first-mentioned leaf, plastic material in the glazing frame, 105 and a pane positioned against the edge of the curved leaves of the frame strips and embedded in the plastic material, substantially as described.

2. The combination with a main sash 110 frame, of a glazing frame secured in the sash frame, said glazing frame comprising

metal strips bent forming two leaves, one leaf of each strip relatively flat and coincident with a surface of the main sash frame and secured to said surface, the other leaf 5 curved and shorter than the first-mentioned leaf, plastic material in the glazing frame, and a pane positioned against the edge of the curved leaves of the frame strips and 10 embedded in the plastic material, said plastic material located between the edge of the pane and the first-mentioned leaves of the strips, substantially as described.

3. The combination with a main sash frame, of a glazing frame secured in the 15 sash frame, said glazing frame comprising metal strips bent forming two leaves, one leaf of each strip relatively flat and coinci-

dent with a surface of the main sash frame and secured to said surface, the other leaf curved and shorter than the first-mentioned 20 leaf, plastic material in the glazing frame, and a pane positioned against the edge of the curved leaves of the frame strips and 25 embedded in the plastic material, and detachable glazing strips secured in the frame and holding the pane against the glazing frame, substantially as described.

In testimony whereof I have signed my name to this specification in the presence of two subscribing witnesses.

DANIEL J. DUNBAR.

Witnesses:

M. B. CATELL,
CHAS. E. POTTS.
